(57) **CLAIM**

The ornamental design for an eyeglass case, as shown and described.

DESCRIPTION

This application also claims priority to U.S. Design patent application Ser. No. 29/205,824 filed on May 20, 2004, now U.S. Design Pat. No. D525,427.

FIG. 1 is a back, top, and right side perspective view of an eyeglass case in accordance with the first embodiment of the present invention;

FIG. 2 is front elevational view thereof, the back elevational view being a mirror image except for the unclaimed environment;

FIG. 3 is a right side elevational view thereof, the left side elevational view being a mirror image except for the unclaimed environment;

FIG. 4 is a top plan view thereof;

FIG. 5 is a bottom plan view thereof;

FIG. 6 is a back, top, and right side perspective view of an eyeglass case in accordance with the second embodiment of the present invention;

FIG. 7 is front elevational view thereof, the back elevational view being a mirror image except for the unclaimed environment;

FIG. 8 is a right side elevational view thereof, the left side elevational view being a mirror image except for the unclaimed environment;

FIG. 9 is a top plan view thereof; and,

FIG. 10 is a bottom plan view thereof.

The broken lines are for illustrative purposes only and form no part of the claimed design.

The stippled and cross-hatched shade lines shown on the drawing views represents color contrast.
